UNITED STATES PATENT OFFICE.

JOHN E. HARRIS AND JOHN J. HARDENBROOK, OF LIMA, OHIO.

IMPROVEMENT IN BRIDLE-ROSETTES AND GAG-SWIVELS.

Specification forming part of Letters Patent No. **155,796**, dated October 13, 1874; application filed August 29, 1874.

To all whom it may concern:

Be it known that we, JOHN E. HARRIS and JOHN J. HARDENBROOK, of the city of Lima, in the county of Allen and State of Ohio, have invented a new and valuable Improvement in Bridle Rosette and Swivel Combined; and we do hereby declare that the following is a full, clear, and exact description of the construction and operation of the same, reference being had to the annexed drawings, making a part of this specification, and to the letters and figures of reference marked thereon.

Figure 1 of the drawing is a representation of a side view of our bridle rosette and swivel. Fig. 2 is a sectional view, and Fig. 3 a detail view, of the same.

The nature of our invention consists in attaching the gag-rein runner to the rosette by means of the same screw that confines the two parts of the rosette together, which screw forms a pivot for the said gag-rein runner, and allows it to play freely, as will be more fully understood from the following description.

In the annexed drawings, A B designate the two parts constituting the new rosette. The part A is hollow, to receive the straps herein-after referred to; and the part B forms the back plate or washer, and is centrally perforated to receive a pivot-screw, *a*. The front

part or rosette proper may be ornamented in any suitable manner; and the rim of this rosette is cut away at *c* for the passage of the tongue of the gag-rein runner D. This runner, which may be made of leather or metal, is held in place inside of the rosette by means of the pivot-screw *a*, which will allow free play of this runner, that it may accommodate itself to the movements of the horse's head. C designates the brow - band, which is secured in a recess between the two parts of the rosette by means of teeth or spurs, *b'*, which are on the part A, and which enter the part B, and the strap G is confined between the parts A B, by means of one or more spurs, *a*, (shown in Figs. 2 and 3,) and the pivot-screw *a*.

What we claim as new, and desire to secure by Letters Patent, is—

The rosette A B, having the gag-rein runner D connected to it by the pivot-screw *a*, as shown and described.

In testimony that we claim the above we have hereunto subscribed our names in the presence of two witnesses.

JOHN E. HARRIS.

JOHN J. HARDENBROOK.
